UNITED STATES PATENT OFFICE.

ANNA M. LAY, OF LOUISVILLE, KENTUCKY.

BABY'S JINGLE-BELL PIANO.

Application filed May 6, 1924. Serial No. 711,417.

The invention relates to musical toys and provides an article embodying key levers, musical elements adapted to be sounded when the key levers are operated and plates bearing pictorial or other matter to be displayed and in cooperative relation with the key levers to be actuated thereby and in turn to act as counterweights to insure a quick return of the levers to normal position.

Other objects and advantages will be apparent and suggest themselves as the nature of the invention is understood.

While the drawings illustrate an embodiment of the invention it is to be understood that in adapting the same to meet different conditions and requirements, various changes in the form, proportion and minor details of construction may be resorted to without departing from the spirit of the invention.

Referring to the accompanying drawings forming a part of the application:

Figure 1 is a front view of a toy piano embodying the invention, the dotted lines showing two of the keys depressed and the plates associated therewith elevated.

Figure 2 is a top plan view of the toy,

Figure 3 is a transverse sectional view,

Figure 4 is a view similar to Figure 3, showing the key depressed and the coacting plate elevated,

Figure 5 is a sectional detail on the line 5-5 of Figure 3, and

Figure 6 is a detail view of one of the plates.

Corresponding and like parts are referred to in the following description and designated in the several views of the drawings by like reference characters.

The toy comprises a case 1 having an extension front 2 similar to the case of a piano so as to receive the projecting ends of key levers 3 which are mounted upon a rod 4 and spaced apart by interposed wash-

ers 5. A slot 6 is provided in the rear portion of the top of the case and admits of the projection of plate 7 therethrough. A plate 7 is provided for each of the keys 3 and is loosely connected to the rear end of the key so as to move therewith and these plates may be of any suitable material and may operate as counterweights for the key levers to insure a quick return thereof to normal position. That portion of the plate which is adapted to project beyond the top of the case when the key is depressed may bear a picture or be provided with any desired matter to be displayed either to afford amusement, instruction or both. Pins 8 are shown as the preferred connecting means between the plates 7 and the key levers 3.

A musical element 9 is positioned to be operated by each of the keys 3 and, as shown, the same consists of an ordinary sleigh bell which is mounted upon a wire 10 held under tension by a spring 11, and when the key 3 is depressed, the musical element is sounded and the plate 7 is simultaneously projected, and when the key is released it is quickly returned to normal position by the weight of the plate. It is to be understood that the case and the keys may be finished in any preferred way, and that the keys may be of contrasting or any preferred color, thereby enabling a child to learn and distinguish the various colors.

What is claimed is:—

A musical toy comprising a case, keys pivoted within the case, a supporting element located within the case above the rear portions of the keys, a spring holding the supporting element under tension, and bells mounted upon the supporting element and adapted to be struck by the keys on the actuation of the latter.

In testimony whereof I affix my signature.

ANNA M. LAY.
